UNITED STATES PATENT OFFICE.

GORDON S. JOHNSON, OF WHEATON, ILLINOIS, ASSIGNOR TO GENERAL HIGHWAYS SYSTEM, INCORPORATED, OF CHICAGO, ILLINOIS.

OUTDOOR ADVERTISING SIGN.

Application filed June 30, 1924. Serial No. 723,356.

The invention relates to out-door advertising signs and has particular reference to means whereby distinctive and ornamental borders may be economically manufactured and cheaply, easily and quickly applied by unskilled workmen to old signs already erected or new ones to be erected.

The usual out-door advertising sign is without any material ornamentation, except that which appears on the sign-board itself, and is, therefore, quite unattractive. All out-door advertising signs have the same general marginal appearances.

By my invention it is possible to apply a symmetrical border of sufficient area to not only cover up posts or unsightly supporting structures, but to also bear decorative features, giving individuality and variations to signs by ornamenting the border so that the ornamentation can be seen at considerable distances.

The invention includes, in general, an ornamental border for out-door signs, preferably arranged at the top and the bottom and the sides of the sign-board, and so constructed that it may be readily added and adjusted in relation to the sign-board by unskilled labor. Any means of attaching the border in proper relation to the sign may be employed. The border may be made in sections for convenience in handling, and wood or sheet metal bearing any desired design may be employed.

The border may be ornamented in colors, and the designs on various borders may simulate any natural or artificial objects. The decorating may be done by stencils or hand painting, and on account of the fact that the border is an added element, the work may be done very economically at the factory.

The advantages of these inexpensive, ornamental, readily-appliable borders make it possible to give to out-door advertising signs each an individuality which has not been possible by the construction now in use. By using borders embodied in this invention it is possible to relieve the highway of present unsightly and, therefore, objectionable signs, and to substitute therefor highly ornamental signs of varied appearances. Present constructions, as employed in out-door signs, make all signs alike in so far as their general appearances are concerned. By my invention it is possible to get such a

dissimilarity between signs that they will not have a monotonous appearance even when they are placed close together.

A further advantage derived from the use of my invention is that the installation of signs may be performed by unskilled labor, it being immaterial whether or not the supporting posts and other parts thereof are too small to receive adequate ornamentation, or are accurately placed, or are made of inferior material, inasmuch as the ornamental borders cover all imperfections of workmanship and materials.

Also the ornamental border may be so proportioned relatively to the sign-board as to give to the entire sign symmetry which cannot otherwise be attained.

Furthermore these ornamental borders may be disposed in planes, each of which is in front of that of the sign-board so as to give in each case an appearance of some depth to the sign.

The drawing shows the details of the invention,

Figure 1 being a view of the sign in elevation;

Figure 2 being a sectional view taken on the line 2-2 of Figure 1;

Figure 3 being a sectional view taken on the line 3-3 of Figure 1;

Figure 4 being a view in section of the ornamental border and parts of an ordinary sign to which said border is added, and

Figure 5 being a view of the tongue used as a support.

The supporting posts are designated by the numeral 1, and these posts are connected at the top by a beam 2 united to said posts by angle irons 3 disposed at each end thereof. This beam may be used to space the posts when the workman is setting them in the ground, and thereafter attached to the posts.

The border comprehends removable sections, 4, 5, 6, 7, respectively arranged to constitute one side, the top, the other side and the bottom of said border. The bottom section may, in some instances, be omitted.

The section 4 (or the section 6) is secured to a post 1 in the manner shown in Figure 2, wherein appears said section 4 made of sheet metal reinforced by wooden strips 8, 9. An eye 10 carried by the strip 8 receives the vertical tip of a tongue 11 which tongue is attached to the inner side of the post 1, whereby said section 4 may be set in place by a

downward movement which causes said eye 10 to encompass the tip of said tongue 11. These supporting devices are, preferably, disposed proximate the inner edge of the 5 section, and are so arranged that said section rests against the face of the post with its free outer portion extending quite a distance beyond said post. A hook 12, secured to the back of the post by a lag screw 13 and en- 10 gaging an eye 14 fixed to the strip 9, exerts a tensional strain on the section and causes it to seat firmly against the face of the post.

The sign-board 15 has a frame 16 provided with an outstanding marginal flange 17, and 15 to the back of this frame is attached in any suitable manner a sign plate 18, said sign-board, as a whole, being held against horizontal back braces 19 extending from post to post. Wooden cleats 20, attached to the 20 sign-board, engage the under side of the upper back brace, and the upper side of the lower back brace, respectively.

The relative sizes of the sign-board and the ornamental margin are such as to leave a 25 clear space 20^a between these two elements for the flow of air to thus relieve the wind pressure.

The posts 21, and the sign-board and its sign plate, shown in Figure 4, are of the type 30 which is in common use. The ornamental sections may be secured to the sign by nails, or in any other manner without alteration of the sign. This is very advantageous in the installation of the ornamental borders 35 constituting my invention, since, by a very simple means applied to unattractive signs, these signs may be transformed into highly adorned objects which command the favorable attention of all observers.

40 Angle irons 22, having slots 23 and supported by the beam 2, may be employed to

sustain the section 5, lag screws or bolts 24 being used to unite the parts. Should the beam warp, these angle irons may be adjusted to compensate for the distortion and 45 admit of non-alignment of the several angle irons.

While the specific devices herein described are new and useful, the ornamental sectional border is the predominant feature of the invention. 50

Having thus described my invention, what I claim is:

1. A sign having supporting posts arranged at each side thereof and including a 55 sign board, and a separable border for said sign board overlying and concealing said posts.

2. A sign having means for supporting the same, and including a sign board and 60 separable decorative elements arranged at the top and the sides of said signboard and spaced from its edges.

3. A sign including means for supporting a sign board, and a sign board, and a border 65 supported independently of said sign board and obscuring structural elements of said sign.

4. A sign including a replaceable sign board, means for supporting said sign, and 70 an ornamental border obscuring parts of the sign structure and spaced from all sides of said sign board which are proximate said border.

5. The combination of a sign board, a supporting post for said sign board, a section of a border for said sign board secured to said post and extending over and outward beyond a face thereof, and means for drawing said section firmly against said face. 75

In testimony whereof I affix my signature. 80
GORDON S. JOHNSON.
